CONCEALABLE TROUSER SUPPORT

Jerome E. Johnson, 5 Pascack Road, Woodcliff Lake, N.J.

Filed Dec. 20, 1962, Ser. No. 246,118

3 Claims. (Cl. 2—327)

My invention is directed toward trouser supports of the suspender type and more particularly relates to supports of this type that can be worn under a shirt and thus concealed from view.

It is an object of my invention to provide a new and improved type of concealable trouser support wherein the pull of the trouser is exerted against the support and little if any pull is exerted against the shirt of the wearer whereby greater wearing comfort is obtained and the shirt is not crumpled or damaged in any way.

Another object of my invention is to provide a new and improved type of concealable trouser support which need not incorporate back strap connections to the trousers and yet affords equalized shoulder pull whereby when the support is in use and is pulled from the front, the support will not ride up the back of the wearer.

Still another object of my invention is to provide a new and improved type of concealable trouser support utilizing two front straps having clasps which are engageable with corresponding mating clasps secured to the top of the trousers, the clasps being so constructed as to permit the wearer's shirt (which is clamped between the support and trouser clasps) to be manually moved freely in any direction after the trouser and support clasps are engaged.

Yet another object of my invention is to provide a new and improved type of trouser support utilizing two front straps having clasps which are engageable with corresponding mating clasps secured to the top of the trousers wherein the wearer can engage or disengage the support and trouser clasps without removing a suit coat (should he be wearing same) and wherein upon disengagement of the clasps, the wearer can raise or lower his trousers at will.

Still a further object is to provide a new and improved concealable trouser support of the character indicated wherein the support and trouser clasps can be disengaged and reengaged from the outside of the shirt without reaching thereunder and without producing any movement of the shirt out of a previously selected position and wherein the shirt after clasping will not by itself ride out of position whereby the shirt can be held in any wanted position.

Yet a further object is to provide a new and improved type of concealable trouser support of the character indicated which can be manufactured easily and inexpensively.

These and other objects of my invention will either be explained or will become apparent hereinafter.

In accordance with the principles of my invention, my concealable trouser support comprises first and second vertical shoulder loops adapted to be supported by the left and right shoulders of the wearer and to be worn under the shirt. First and second vertical front straps extend downward from the first and second loops respectively, and terminate at first and second rigid support clasps respectively. Each support clasp is registerable with a corresponding one of first and second trouser clasps secured to the inner front portion of the top of the trousers. Each support clasp is readily engageable and disengageable from the corresponding trouser clasp; when a support clasp engages the corresponding trouser clasp, a portion of the wearer's shirt is held in position therebetween. The support and trouser clasps can each include a magnet or can be so constructed as to permit the shirt to be manually moved freely in any direction after

2

either or both pairs of clasps have been engaged. Moreover, either or both pairs of clasps can be disengaged and reengaged without producing any movement of the shirt out of position.

5 In order to provide great wearing comfort and at the same time prevent the shirt from being damaged in any way, the trouser pull is to be exerted through the support to the shoulders of the wearer with substantially no pull being exerted on the shirt to cause crumpling or damage thereto. To this end, the rear top portion of both of the first and second loops are joined in two places by an X-shaped support member extending in a generally horizontal direction therebetween.

Depending upon the size of the wearer's shoulders and 15 waist, it is sometimes advisable to provide a horizontal member extending between and secured to both of the first and second front straps. In addition when the user wears extremely loose fitting trousers, a means for supporting the trousers at the rear can be incorporated into my trouser support.

The trouser clasps can be permanently affixed to the trousers, but preferably are designed to be readily secured to or removed from the trousers.

Illustrative embodiments of my invention will now be 25 described in more detail with reference to the accompanying drawings wherein:

FIG. 1 is a perspective view of one form of my concealable trouser support in operative use;

30 FIG. 2 is a perspective view of my trouser support somewhat modified from the form shown in FIG. 1;

FIG. 3 is a plan view of one form of a trouser clasp as employed in my invention;

FIG. 4 is a plan view of a support clasp which operates with the trouser clasp of FIG. 3;

35 FIG. 5 is a side cross sectional view showing the clasp of FIGS. 3 and 4 engaged with a portion of the wearer's shirt held in position therebetween;

FIGS. 6 and 7 are plan and side views respectively of a somewhat modified form of the trouser clasp of FIG. 3;

40 FIGS. 8 and 9 are plan views respectively of another form of mating trouser and support clasps;

FIG. 10 is a side cross sectional view showing the clasps of FIGS. 8 and 9 in engaged relationship;

45 FIG. 11 is a perspective view of the clasp of FIG. 4 in open position;

FIG. 12 is a perspective view of the clasp of FIG. 4 in closed position;

FIG. 13 is a side cross sectional view similar to that 50 of FIG. 5 but showing somewhat modified clasps; and

FIG. 14 is a side cross sectional view similar to that of FIG. 13 but showing somewhat modified clasps.

Referring now to FIG. 1, a person is shown wearing a shirt 12 and a pair of trousers 14. A concealable 55 trouser support is worn underneath the shirt. The support comprises a first vertical loop 16 fitting about the left shoulder of the wearer and a second vertical loop 18 fitting about the right shoulder of the wearer.

A first vertical front strap 20 extends downward behind 60 the front of the shirt and is secured to the bottom of loop 16. Similarly a second vertical front strap 22 extends downward behind the front of the shirt and is secured to the bottom of loop 18. Conventional buckles or other means 24 carried by each of straps 20 and 22 permit the length of each of these straps to be individually 65 adjusted.

Separate rigid support clasps 26 are secured to the bottom of each of straps 20 and 22.

An X-shaped strap member 28 extends between loops 16 and 18 and is secured thereto in the top rear regions thereof whereby this member 28 rests in the rear top portion of the wearer's shoulders. Straps 20 and 22 can

be joined together by a horizontal strap 30 formed from two joinable half straps.

When the user wears extremely loose trousers, the support can be modified as shown in FIG. 2. The support of FIG. 2 uses a band 32 which completely encircles the waist in place of the member 30 of FIG. 1, and, in addition, is provided with a third vertical rear strap 34 which extends downward from the X-shaped strap member 18.

In the arrangements of FIGS. 1 and 2, each of vertical straps 20, 22 and 34 terminate in a rigid support clasp 26 (shown in block form in FIGS. 1 and 2) which is engageable with a corresponding trouser clasp secured to the inside of the trousers.

FIG. 3 shows one such trouser clasp. It comprises a flat sheet-like element 40 formed, for example, of plastic and having a plurality of peripherally placed holes 42 through which thread can pass to secure element 40 to the inside of the top of the trousers. Projecting outward from the center of element 40 is a central support 44 in the form of a T. The top arm 46 of the support extends horizontally away from and parallel to element 40. The arm 46 has a central bore through which a shaft extends. Two cylinders 48 having central bores which accommodate the shaft are secured to opposite ends to form a horizontal member 49 which is free to rotate within arm 46. Alternatively, the trouser clasp can be modified as shown in FIGS. 6 and 7 where the element 40 can be bent into a U-shape to fit over the top edge of the trousers whereby the support can be easily secured to and removed from the trousers by tightening or loosening screw 50.

The mating support clasp as shown in FIG. 4 can comprise a metal plate 60 again provided with peripheral holes 62 through which thread can pass to secure the plate to the bottom of the appropriate vertical strap. Secured to plate 60 are two vertical metal strips 64 each supporting an inverted U-shaped guard 66 secured at both ends of the U to the corresponding strip, each guard being perpendicular to the appropriate strip. Both guards are vertically parallel.

A lower horizontally extending L-shaped member 68 spans both vertical strips and is secured thereto. An upper horizontally extending L-shaped member 70 is secured to a second plate 72 which can be moved between strips 64 to a first position at which members 68 and 70 are so widely separated that the horizontal member 49 formed by the two cylinders 48 of the trouser clasp cannot be held therebetween. This position is that in which the trouser and support clasps are disengageable from each other as shown in FIG. 11.

Plate 72 can also be moved between strips 64 to a second position at which the members 68 and 70 are so closely separated that the horizontal member 49 formed by the two cylinders 48 of the trouser clasp can be held in place by members 68 and 70 and guards 46 whereby this horizontal member is free to rotate but cannot be removed. This second position is that in which the trouser and support clasps are engaged as shown in FIG. 12.

This engaged position with the shirt held in position by the engaged clasps is shown in FIG. 5. Note that the shirt position can be adjusted by the user merely by pulling the shirt to any position desired since the horizontal member 49 is free not only to rotate as the shirt is pulled but can also slide back and forth between the guards 66 and toward and away from plate 60.

The engageable and disengageable positions previously described are obtained as shown in FIG. 4. A horizontal metal strip 74 spanning the upper ends of both vertical strips 64 has a horizontal slot 76 which accommodates the vertical shaft 78 extending between and secured to a top control button 80 and a smaller bottom button 82. Button 82 rides in a contoured slot 84 in plate 72. When the control button 80 is slid to the extreme right position in slot 76 (as shown) button 82 is positioned at the ex-

treme right in contoured slot 84; this is the engageable position. When button 80 is slid to the extreme left position in slot 76, button 82 is positioned at the extreme left in contoured slot 84; this is the disengageable position.

Another type of trouser-support clasp arrangement is shown in FIGS. 8-10. The trouser clasp which as before can be removably attached and detached from the trousers can comprise a U-shaped element 42 having two oppositely disposed vertical brackets 90 which together hold in place a magnet plate 92 (formed for example of Alnico). The support clasp can comprise a plate 100 having two oppositely disposed horizontal brackets 102 which together hold in place a second magnet plate 104.

By placing plates 90 and 104 together (with the shirt subtended therebetween), the clasps can be engaged by magnetic force. Note that the combination of horizontal brackets 102 and vertical brackets 90 prevents plates 90 and 104 from relative sliding movement. This action is required, because the wearer's movements could otherwise produce such a sliding movement which could inadvertently disengage the magnet clasps.

FIG. 13 shows in cross section a first modification of the clasps shown in FIGS. 3-5 and 11-12. In FIG. 13, the horizontal member 49a secured to the U-shaped element 40 does not rotate and in cross section has the shape of an L. The support clasp in FIG. 13 is controlled by button 80 in the same manner as before. However, L-shaped member 70 of FIGS. 4 and 5 is replaced by a straight horizontal member 70a. [This change in shape is necessary because of the difference in shape between member 49 of FIG. 3 and member 49a of FIG. 13.]

A slight modification of FIG. 13 is shown in FIG. 14 where the L-shaped horizontal member 49b points upward in place of the downward pointing horizontal member 49a of FIG. 13. Button 80 controls the support clasp as before. However, in this case L-shaped member 68 of FIGS. 4 and 5 is replaced by a straight horizontal member 68a.

When desired, my concealable trouser support, instead of being a separate unit, can be secured to or embodied in either a shirt or vest.

While I have shown and pointed out my invention as applied above, it will be apparent to those skilled in the art that many modifications can be made within the scope and sphere of my invention.

What is claimed is:

1. A concealable trouser support adapted to be worn by a person wearing trousers and a skirt, the skirt having its bottom edges tucked inside the waist band of the trousers, said support comprising a structure to be worn underneath the shirt and including first and second vertical loops, each loop being adapted to fit about a corresponding shoulder of the wearer, first and second vertical straps, each strap depending downward from a corresponding one of said loops toward said waist band, first and second support clasps, each support clasp being respectively secured to the bottom end of the corresponding strap, and a strap member being adapted to extend generally horizontally across the back of the wearer between the rear top portions of both loops and being secured to both loops; and first and second trouser clasps being adapted to be secured to said waist band, each trouser clasp being engageable with a corresponding support clasp in such manner that the shirt is held between the trouser and support clasps, each pair of engaged clasps having cooperating male and female clasp members which when engaged exhibit a relative clearance therebetween at least equal to the thickness of said shirt to permit the wearer, after clasp engagement, to move portions of the shirt with respect to said trousers to adjust the fit of the shirt without causing clasp disengagement.

2. A concealable trouser support adapted to be worn by a person wearing trousers and a shirt, the shirt having its bottom edges tucked inside the waist band of the trousers, said support comprising a structure to be worn

underneath the shirt and including first and second vertical loops, each loop being adapted to fit about a corresponding shoulder of the wearer, first and second vertical straps, each strap depending downward from a corresponding one of said loops toward said waist band, first and second support clasps, each clasp being respectively secured to the bottom end of the corresponding strap, each support clasp having a cylinder-like member, and a strap member being adapted to extend generally horizontally across the back of the wearer between the rear top portions of both loops and being secured to both loops; and first and second trouser clasps being adapted to be secured to said waist band, each trouser clasp having a plate-like element carrying first and second parallel spaced apart members spaced apart from said element and parallel thereto, the space between the element and the first and second members defining a region in which one of said cylinder-like members can be fitted loosely, each trouser clasp having means for moving the first and second members into alternative open and closed positions, the separation between said first and second members in the open position being larger than the diameter of one of said cylinder-like members, the separation between said first and second members in the closed position being smaller than said diameter, each trouser clasp being engagable with a corresponding support clasp when the cylinder-like member of the trouser clasp is inserted in said region of said corresponding support clasp and the first and second members of said corresponding support clasp are in the closed position, the shirt adapted to be held between the engaged trouser-support clasps in such manner that portions of the shirt can be moved freely with respect to the trousers to adjust the fit of the shirt without disturbing the engagement of said engaged clasps.

3. A support-trouser clasp arrangement for detachably securing first and second articles of apparel together and comprising a support clasp detachably securable to said first article and having a horizontal cylinder-like member,

and a trouser clasp detachably secured to the second article and having a plate-like element carrying first and second parallel spaced apart members spaced apart from said element and parallel thereto, the space between said first and second members and said element defining a region in which said cylinder-like member can fit loosely, each trouser clasp having means for moving the first and second members into alternative open and closed positions, the separation between said first and second members when in the open position being larger than the diameter of said cylinder-like member, the separation between said first and second members when in the closed position being smaller than said diameter whereby when said cylinder-like member is inserted in said region and said first and second members are in the closed position, said cylinder-like member can be moved in said region but cannot escape therefrom.
